UNITED STATES PATENT OFFICE.

JOHN SELDON ADAMSON, OF HOUSTON, TEXAS, ASSIGNOR OF ONE-HALF TO DENIS J. LYNCH, OF HOUSTON, TEXAS.

DISPLAY-RACK.

1,103,728.

Specification of Letters Patent.

Patented July 14, 1914.

Application filed September 23, 1913. Serial No. 791,442.

To all whom it may concern:

Be it known that I, JOHN SELDON ADAMSON, a citizen of the United States, residing at Houston, in the county of Harris and State of Texas, have invented certain new and useful Improvements in Display-Racks; and do hereby declare the following to be a full, clear, and exact description of the invention, such as will enable others skilled in the art to which it appertains to make and use the same.

This invention comprehends improvements in display racks and relates more particularly to those which are adapted to be removably secured in a show window or other similar places.

One of the objects of the invention is to provide a display rack formed of a plurality of bars which are capable of being arranged in various combinations so as to form racks of different styles.

Another and more specific object of the invention is to provide a novel means for connecting the bars which form standards and cross pieces in different relative positions.

A further object of the invention is to provide a display rack which shall be of extremely simple construction, cheap to manufacture and very strong and durable.

The invention also aims to generally improve devices of this nature to render them more useful, practical and commercially desirable.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a fragmentary perspective view, showing one form of rack which may be constructed by the use of the bars and connecting means, Fig. 2 is a perspective view, showing another style of rack, Fig. 3 is a vertical sectional view through the form of rack shown in Fig. 1, and Fig. 4 is a fragmentary sectional view, showing the connection between the upper cross bars and standards, as illustrated in Fig. 2.

Referring in detail to the drawings by numerals, 5 designates a portion of a show window floor, which is provided with a plurality of base sockets, generally designated 6. As shown in Fig. 2, each socket comprises an internal threaded body portion 7 and an annular flange 8 formed about the upper edge of said body portion, said flange being seated within a countersink formed in the upper surface of the floor 5. It is desirable to secure these base sockets at equal distances from one another over the entire floor of a show window in order that as many display racks as desired may be secured in a window and in order that the display racks may be placed in different positions in the window.

In Fig. 1 I have shown a portion of the rack, which is formed of a plurality of standards 9, cross arms 10 and connecting rods 11. Each of the bars has secured in its end a tubular rod 12 which is received in a longitudinal recess 13 formed in the standard and which is externally threaded upon one end, as indicated by the numeral 14. These tubular rods are preferably secured within the recesses of bores 13 by means of bolts 15 and nuts 16. The bolts extend transversely through the bars and through openings formed adjacent the inner ends of the rods 12. The bars are also provided intermediate their ends with one or more sockets 17, dependent upon the length of the bar. Each socket comprises a tubular internally threaded body 18 which extends transversely through the bar and which is provided with a flange 19 on one end thereof. The flange is preferably positioned within the countersink formed in the bar so that it will come flush with the surface thereof. A nut 20 is rigidly secured to the other end of the body 18 and provides a means whereby the socket may be rotated with respect to the bar.

The lower cross piece 10, shown in Fig. 1, is secured to the upper end of the lowermost standard 9 by threading the extremity of the uppermost threaded rod carried by said standard into the socket carried by the cross piece, as clearly shown in Fig. 2. The upper cross piece 10 is secured in position by threading the lower end of the connecting rod 11 into the top of the socket 17 and then threading the upper end of this connecting rod into the socket carried by the upper

cross piece 10. Since the sockets 17 are rotatable with respect to the bars to which they are secured, it is very easy to thread the ends of the connecting rod 11 therein.

6 In Fig. 3, I have shown a slightly different form of rack, wherein one main standard 9 is employed and two ordinary standards 9'. The lower end of the standard 9 is threaded into one of the sockets in the 10 floor of a show window and a cross piece 10 is secured intermediate its ends to the top of this standard. The secondary standards 9' are threaded into the sockets 17, positioned adjacent the ends of the cross arm 10 15 and carry upon their upper extremities short cross arms 10'. These last mentioned arms support a glass plate 21 upon which various articles may be placed for display.

It is to be understood that all of the 20 standards and cross pieces shown and described are of a similar construction and differ from one another only as to their length. It is intended that these standards and cross pieces be sold in sets, each set to 25 contain a large number of pieces of various lengths, so that the user may form display racks of different styles. Although I have shown all of the bars as being square in cross section, I desire to have it understood

that these pieces may be made different 30 shapes without departing from the scope and spirit of the invention as claimed.

Having thus described my invention, I claim:

1. A display rack unit, comprising a bar, 35 a screw threaded rod projecting longitudinally from each end of the bar, and a plurality of sockets extending transversely through the bar, each of said sockets comprising a tubular body internally threaded 40 having a flange on one end, and a nut rigidly secured to the other end, whereby the body may be rotated.

2. In a display rack, a pair of units, each comprising a bar formed with a transverse 45 opening circular in cross section, and a socket rotatably secured within said opening, each socket comprising a tubular body internally threaded having a flange on one 50 end, and a nut rigidly secured to the other end; and a screw threaded connecting rod projecting into said socket.

In testimony whereof I affix my signature in presence of two witnesses.

JOHN SELDON ADAMSON.
